CLAIM

The ornamental design for a toy car, as shown and described.

DESCRIPTION

FIG. 1 is a front elevation view of a toy car, showing my design.

FIG. 2 is a rear elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a top, front, left side perspective view thereof.

FIG. 8 is a bottom, rear, right side perspective view thereof.

FIG. 9 is a perspective view thereof, shown in a state that a front part of the toy car is opened.

FIG. 10 is an enlarged view of an area labeled 10 in FIG. 7.

FIG. 11 is an enlarged view of an area labeled 11 in FIG. 7; and,

FIG. 12 is an enlarged view of an area labeled 12 in FIG. 7. The details shown in broken lines form no part of the claimed design.
